UNITED STATES PATENT OFFICE.

EDWIN L. PAGE, OF BRIDGEPORT, CALIFORNIA.

SAFETY-RAZOR.

1,387,935.

Specification of Letters Patent. Patented Aug. 16, 1921.

Application filed August 18, 1919. Serial No. 318,075.

To all whom it may concern:

Be it known that I, EDWIN L. PAGE, a citizen of the United States, and a resident of Bridgeport, county of Mono, and State 5 of California, have invented a new and useful Safety-Razor, of which the following is a specification.

My invention relates to safety razors and particularly to the type having a thin double 10 edged reversible blade.

An object of the invention is to provide a safety razor in which the razor blade guard is disposed on the blade upon the side opposite to that on which the cut hair and lather 15 collect during the shaving operation. In this manner the guard does not interfere with the cutting of the hair and permits a free movement of the lather and cut hair during the operation of the razor.

Another object of the invention is to provide a safety razor in which the razor blade guard maintains a fixed coöperative relation with respect to the cutting edges, regardless of the variation in the width of 20 the blade caused by the continual re-sharpening of the edges thereof.

A further object of the invention is to provide a handle for a razor having a double edged blade, whose position may be readily 25 changed, in order that the blade may be held at the proper cutting angle regardless of the particular cutting edge that is used.

The invention possesses other objects and features of advantage, some of which, with 30 the foregoing, will be set forth in the following description of the preferred forms of my invention which is illustrated in the drawings accompanying and forming part of the specification. It is to be understood 35 that I do not limit myself to the showing made by the said drawings and description, as I may adopt variations of the preferred forms within the scope of my invention as 40 set forth in the claims.

Referring to said drawings:

Figure 1 is a side elevation, partly in section, of the razor of my invention. The sectional portion being taken through the clamping means of the razor.

Fig. 2 is a perspective view of one of the razor blade guards.

Fig. 3 is a perspective view of the perforated guard.

Fig. 4 is a perspective view of the blade.

Fig. 5 is a perspective view of the supporting member.

Fig. 6 is a side elevation, partly in section, of the handle.

Fig. 7 is a cross sectional view of the razor taken through the guard adjusting mechanism, the guards being shown in their extended or inoperative position.

Fig. 8 is a cross sectional view similar to Fig. 7, with the exception that the supporting member is included and the guards 65 are shown in their operative position with respect to the cutting edges of the blade.

Fig. 9 is a cross sectional view similar to Fig. 7, of a slightly modified form of the razor.

Fig. 10 is a vertical cross sectional view showing my invention as applied to a razor having a single cutting edge. The guard is shown disengaged from the cutting edge of the blade.

Fig. 11 is a vertical cross sectional view similar to Fig. 10, showing the guard in coöperative relation with the cutting edge of the blade.

Briefly stated my invention comprises a 80 set of guards which are disposed on the "clean" side of the blade, each guard being arranged to coöperate independently with the cutting edge with which it is associated. Means are provided for normally holding 85 the guards out of coöperative engagement with the cutting edges so that the blade may be initially positioned on the razor. Means are also provided for causing the guards to coöperatively engage the cutting edges in 90 a fixed or unvarying relation regardless of variations that may occur in the width of the blade. Means are also included for enabling the blade to be readily held at the proper cutting angle regardless which cutting edge it is desired to use.

A detailed description of my invention follows:

The safety razor of my invention, in broad terms, is of the type which employs a double-edged blade of such thinness that external support is required to give rigidity to its cutting edges. Safety razors of this type are usually provided with a razor blade guard which is arranged on the blade upon 100 the side on which the cut hair and lather collects. This construction in many instances prevents the free movement of the lather and cut hair and more or less impairs the smooth shaving qualities of the razor. In 105 accordance with my invention the guards are disposed on the blade upon the side

which faces the roots of the hair when the razor is shaving the beard. In this manner the guards do not interfere with the cutting operation of the hair or impede its passage 5 after it is cut.

In the present form the cutting edges 3 and 4 of the blade 5 are provided with thin straight edged guards 6 and 7 respectively, whose body portions 8, are arranged to 10 overlie each other. The body portion of the guard 6 is sufficiently recessed to enable the guard 7 to lie in substantially the same transverse plane as the guard 6. The guards coöperate with their associated edges independently of each other and are provided 15 at their ends with projections 9 which are arranged to engage the cutting edges 3 and 4 when the razor is assembled.

Means are provided for holding the 20 guards extended with relation to each other in order that the blade may be placed between the two pairs of projections 9 on the guards. Formed on the guard 6 is a set of integral studs 12 which are adapted to engage alined perforations or slots 13 provided in the guard 7. A set of studs 14 is also provided on the guard 7, the studs being so positioned on the guard that they lie in proximity to the studs 12 of the guard 6 when 25 the studs 12 extend through the perforations 13. The studs 12 are provided with springs 15 which are arranged to press against the studs 14 to hold the guards in extended relation. The blade, which is suitably slotted to clear the studs, may then be 30 inserted between the guard projections.

Means are also provided for moving the 35 guards inwardly after the blade has been inserted between the projections, in order that the said projections, may engage the blade and hold the guards in fixed relation to the cutting edges, regardless of any variation that may occur in the width of the blade. Arranged to lie on the reverse side of the 40 blade is a supporting member 17 which is provided with means for effecting engagement of the projections and blade. Secured to the studs 14 and disposed on the side thereof opposite to that against which the 45 spring 15 presses, are springs 18 having considerably less resilience than the springs 15. The supporting member is provided with slots 19 which are adapted to engage the springs 18 and the studs 12 to cause the 50 projections to be drawn toward each other to yieldingly engage the blade and hold the guards in proper relation to the cutting edges. It will be noted that the guard projections are arranged to engage the cutting 55 edges of the blade and since the projections are fixed to the guard, the same relation must always exist between the guard and its associated cutting edge whenever the 60 projections properly engage the cutting edges. As may be seen by referring to Fig. 65

8, the guards may still move inwardly for a considerable distance if required, and since the engagement between the projections and the blade is of a yielding nature, any normal variation that may occur in the 70 width of the blade as when the same has been sharpened, will not prevent the proper engagement of the projections and the blade.

Any convenient means may be provided 75 for detachably clamping the razor together. In the present form the guard 6 is provided with a centrally disposed screw threaded stud 21 which is arranged to pass through suitable apertures 22, 23 and 24 provided in 80 the guard 7, blade 5, and supporting member 17 respectively. A handle 25, screw threaded internally, is arranged to engage the portion of the stud which projects beyond the supporting plate, to clamp the 85 blade between the supporting plate and guards. The body of the handle is bent to enable the razor to be readily held at the proper cutting angle and the head of the handle is provided with a spring pressed 90 cap 27 which is adapted to press against the supporting member and thereby provide a yielding engagement between the handle and supporting member. This construction permits the handle to be turned to enable 95 the razor to be held at the proper cutting angle for either edge without affecting the clamping of the razor.

In the drawings all of the figures with exception of Fig. 1 show the parts inverted 100 since these figures represent the razor not fully assembled and it is in this inverted position that the razor is preferably assembled. In assembling the razor the first step consists in placing the guard 7 upon the 105 guard 6. The blade is next placed in position and is followed by the supporting member. The handle is then added to clamp the parts together.

In disassembling the razor the assembling 110 steps are substantially reversed.

In Fig. 9, I have shown a slightly modified construction. In this form the ends of the springs 15 and 18 are extended and engage in suitable recesses 29 and apertures 115 31 respectively. This prevents the springs from being bent out of proper position when handled roughly.

In Figs. 10 and 11, I have shown my invention as applied to a razor having a single 120 cutting edge. The construction of this form of the invention is quite similar to that of the double edge type, with the main exception that a backing 33 is substituted for the guard 6. In this embodiment the studs 12 125 are formed with integral tapering wings 34. These wings may be substituted for the springs 15 in either form of the invention. When the guard 7 is being placed on the backing 33, the apertures 13 of the guard 7 130

engage the sloping sides of the wings and cause the guard to gradually move outwardly thereby enabling the blade to be placed in the proper position preparatory to 5 its engagement with the guard projections.

I claim:

1. In a razor, the combination with a perforated blade having two opposite cutting edges, of an independent guard for each 10 cutting edge, arranged on one side of said blade, means on said guards arranged to extend through the perforation in the blade for holding the guards out of operative relation with respect to said cutting edges, and a 15 supporting and guard adjusting member disposed on the other side of said blade.

2. In a razor, the combination with a perforated blade having two opposite cutting edges, of an independent guard for 20 each cutting edge, projections on said guards for engaging the cutting edges adjacent the ends thereof, means on said guards arranged to extend through the perforations in said blade for normally holding said projections 25 spaced outwardly from said edges and a supporting member arranged to move the said projections inwardly to resiliently engage the blade edges.

3. In a razor, the combination with a blade 30 having a cutting edge, of a guard coöperating with said edge, a supporting member adapted to engage said blade, and means operative by the movement of said member in a plane substantially perpendicular to that 35 of the blade for moving said guard in a plane substantially parallel to that of said blade.

4. In a razor, the combination with a blade 40 having a cutting edge, of a guard coöperating with said edge, means on said guard for engaging said edge, a supporting member adapted to support said blade, and means operative by the movement of said member in a plane substantially perpendicular to 45 that of the blade for pressing said edge engaging means inwardly to resiliently engage said cutting edge.

5. In a razor, the combination with a 50 perforated blade having a cutting edge, of a guard for said edge, projections on said guard for engaging the end portions of said edge, means coöperating with said guard passing through the perforations in said blade for normally holding said projections 55 spaced outwardly from said edge, a perforated supporting member coöperating with said guard and arranged to move said projections inwardly to resiliently engage the blade edge, clamping means passing through 60 the perforations in said blade and supporting member, and a handle engaging said clamping means and disposed on said supporting member.

6. In a razor, the combination with a perforated blade, having two opposite cutting edges, of a guard for one of said edges, 65 studs extending from said guard, springs on said studs, a perforated guard for the other of said cutting edges, said studs and springs being arranged to pass through the perforated guard and extend the guards with respect to each other, studs on said perforated guard, springs on said studs of lesser resiliency than said first springs, a perforated supporting member through which all 75 of said springs and studs extend and adapted to press against the studs of said first guard and the springs of said perforated guard, means for detachably clamping the blade between said guards and supporting 80 member, and a handle disposed on said supporting plate.

7. In a razor, the combination with a thin perforated blade having two opposite cutting edges, of a guard for one of said cutting edges, studs springing from said guard and provided with a resilient portion, a perforated guard for the other cutting edge, and arranged with said first guard on one side of the blade, said studs being arranged 90 to pass through the perforated guard and extend the guards with relation to each other, projections on said guards for engaging the edges of the blade, said projections being disengaged from said edges while the 95 guards are in said extended position, studs springing from said perforated guard and provided with a resilient portion, said portion having less resiliency than the resilient portion of said first named studs, and a 100 perforated supporting member disposed on the free side of said blade and arranged to engage the studs of said first guard and the resilient portions of said perforated guard to move the guards toward each other and 105 thereby cause the projections on the guards to resiliently engage the blade edges.

8. In a razor, the combination with a perforated blade having a cutting edge, of a guard arranged to lie on one side of said 110 blade, means on said guard for engaging the end portions of said edge, a perforated supporting member arranged to lie on the other side of said blade, and means on said guard arranged to extend through said blade and 115 supporting member adapted to be engaged by the latter to move said edge engaging means into resilient engagement with said edge.

In testimony whereof I have hereunto set 120 my hand at Bridgeport, California, this 4th day of August, 1919.

EDWIN L. PAGE.
